UNITED STATES PATENT OFFICE.

CHARLIE ELMER BROWN, OF FINDLAY, OHIO.

ROUNDABOUT.

1,418,775.

Specification of Letters Patent. Patented June 6, 1922.

Application filed June 18, 1921. Serial No. 478,580.

To all whom it may concern:

Be it known that I, CHARLIE ELMER BROWN, a citizen of the United States, residing at Findlay, in the county of Hancock and 5 State of Ohio, have invented a new and useful Roundabout, of which the following is a specification.

This invention relates to supporting posts for roundabouts or the like, it being the primary object of the invention to provide a sectional post of this character, the sections adapted to telescope to permit the post to be easily handled in the transportation of the same.

15 A further object of the invention is to provide means for supporting the post in its telescoped position, the supporting means being such as to assist in the positioning of the post.

20 A further object of the invention is the provision of means for moving the post to its upright position, and to move the sections thereof to their extended positions.

With the foregoing and other objects in view which will appear as the description proceeds, the invention resides in the combination and arrangement of parts and in the details of construction hereinafter described and claimed, it being understood that 30 changes in the precise embodiment of the invention herein disclosed, may be made within the scope of what is claimed, without departing from the spirit of the invention.

Referring to the drawings:—

35 Figure 1 is a vertical sectional view through a post constructed in accordance with the present invention, and showing the sections thereof in their extended positions.

Figure 2 is a plan view of the same.

40 Figure 3 is a sectional view taken on line 3—3 of Figure 1.

Figure 4 is a fragmental sectional view disclosing a supporting key that contacts with the lower end of the section.

45 Figure 5 is a side elevational view of the post and its support prior to the act of extending the sections thereof.

Figure 6 is a side elevational view of the post in its telescoped position and showing 50 the same as mounted on its support for transportation.

Figure 7 is a sectional view taken on line 7—7 of Figure 5.

Referring to the drawings in detail, the 55 post is shown as mounted on its support, which includes the wheels 5 and body por-

tion 6, the wheels having connection with the body portion 6 in the usual and well known manner. The body portion 6 is preferably inclined towards the rear wheels of the support as clearly shown by Figures 5 and 6 of the drawings, so that the post will be positioned on its support at a decided angle to offer the minimum amount of resistance, while the post is being raised to an upright 65 position.

At the rear of the body portion 6 is a bracket 7 which has bearing members 8 spaced apart to accommodate the shaft 9, the outer ends thereof having connection with 70 the body portion 6 or side arms forming the same, as clearly shown by Figure 7 of the drawings. The shaft 9 is secured against movement, in any suitable manner, there being provided eye bolts 10 for embracing portions of the shaft 9 and having connection with the lower section 11 of the post to hold the post in proper relation with respect to the shaft 9. A band 12 which is curved to conform to the contour of the lower section 75 11 of the mast, embraces the lower portion of the section 11 and has connection with the bracket 7 as through the bolts 13. Thus it will be seen that the post may be pivoted rearwardly, the bearings 8 permitting of 80 movement of the bracket 7 on the shaft 9 to tilt the mast to its upright position.

At the forward end of the body of the support, is formed a U-shaped member 14 which provides a rest for the post as clearly 90 shown by Figure 6 of the drawing. The post includes the lower section 11 which has a lower threaded extremity positioned in the base 15, which has a flange extending therefrom, which flange accommodates the inner 95 ends of the plates 16 which are secured to the bars 17 which form the support for the post when the same is in its upright or vertical position.

The lower section 11 is provided with 100 openings 18 disposed adjacent to the upper end thereof and arranged diametrically opposite each other to accommodate the supporting key 19, which key is of a particular formation and embodies lugs 20 and a handle 21, the handle permitting the key to be readily and easily positioned within the opening, the lugs 20 thereof contacting with the outer surface of the section 11 and closely engaging the same to restrict movement of the key. This key, as clearly shown 105 by Figure 4 of the drawings, provides a sup-

port or rest for the lower extremity of the adjacent upper section, which telescopes in the section 11.

The reference numeral 22 indicates the adjacent upper section which is of a diameter less than the diameter of the section 11 to permit the section 22 to move freely therein, there being provided a flange 23 formed substantially intermediate the ends thereof, which flange provides a support for the member 24 that is supported on the ball bearings 25 disposed between the flange 23 and member 24 to permit the member 24 to revolve around the section 22. This member 24 is provided with sockets to accommodate the usual arms employed in a round-about for supporting the various seats forming a part thereof, the arms being omitted in the present showing, since the same form 20 no part of this invention.

In order that the member 24 may be rotated, a flange 26 is formed at the upper end thereof, the flange being provided with teeth to accommodate the usual propelling gear 25 for rotating the member 24. A tubular member 27 is positioned over the upper end of the section 23 and is secured thereto as by means of the screw 28, the lower end of the tubular member 27 engaging the flange 30 26 to prevent the member 24 moving upwardly on its support or section 22.

Mounted within the section 22, is a tubular section 29 which provides the uppermost section of the post, and this section is supported as by means of the key 30 which passes through registering openings in the wall of the section 22, the detail construction of the key 30 being identical to that shown in detail in Figure 4 of the drawings. 40 Each of the sections 22 and 29 is provided with a longitudinal groove 31, which grooves accommodate the flexible members 32 operating over the pulleys 33 and 34, the ends of the flexible members 32 having connection with the tubular members 22 and 29 associated therewith, adjacent to the lower ends thereof, the opposite ends of the flexible members being wound on the drum 35 which is controlled by the operating handle 36. 50 From the foregoing it is obvious that as the operating handle 36 is moved to operate the drum 35, the flexible members 32 are wound thereon, to move the sections 22 and 29 to their extended position, but when the keys 55 19 and 30 have been removed, the weight of the sections will cause the flexible members 32 to unwind from the drum 35, whereupon the flexible members 32 will take positions within the grooves 31 and sections of 60 the post are moved to their telescoped positions.

The movable support for the post is held stationary, during the operation of moving the post to its upright or standing position, by means of the rods 36' which have

their outer ends embracing portions of the shafts of the support, the inner ends thereof being positioned in the eye bolt 37, turn buckle 38 and being provided to tighten the rods. This eye bolt 37 is positioned in one of the bars 17, there being provided an eye bolt 39 at one end of the bars 17 for providing an anchor for the chain 40 which carries the pulley 41 at the upper end thereof. 75

Secured to the section 22 of the post is a pulley 42 over which the flexible member 43 operates, the flexible member also operating over the pulley 41 while the free end thereof lies in a position to be grasped during 80 the raising and lowering operations to control the movements of the post. A lifting device includes the standards 44 which have pulleys 45 mounted at the upper ends thereof, the lower ends of the standards being 85 bolted to one of the bars 17 of the support as at 46.

Bracing rods 47 have connection with the standards 44 and extend at angles with respect thereto, the lower ends of the bracing rods being bolted to the bar 17 as at 48. Supported by the standards 44 is a drum 49 which is controlled by the operating means 50, which drum accommodates the flexible member 51 that operates over the 95 pulley 45 and has one end thereof secured to the section 22 in any suitable manner.

From the foregoing it will be seen that as the flexible member 41 is wound on the drum 49, that is, when the post is positioned on its support, as shown by Figure 6 of the drawings, the post will be slowly raised to an upright position, whereupon the flexible member 51 may be disconnected from the post. 100

When the post has been moved to its extended position, the brace rods 52 are positioned as shown by Figure 1 of the drawings, the lower ends thereof having connection with the bars 17 of the support as at 53, the upper ends of the rods 52 being threaded 110 in suitable openings provided in the flange 23.

When it is desired to telescope the post, the flexible members 32 are loosened to permit the sections 22 and 29 to telescope, whereupon the flexible member 43 is operated to 115 tilt the post towards the movable support or body 6, it being understood however that an attendant holding the handle 50 allows the flexible member 51 to move gradually, to insure against the post falling too suddenly 120 to its support.

In view of the foregoing detail disclosure, a further detail description as to the operation of the device is believed unnecessary.

Having thus described the invention, what is claimed as new is:—

1. In a device of the character described, a movable support, a post, means for pivotally connecting the post to the movable support, said post including a plurality of tele- 130

scoping sections, each of said sections having a groove extending longitudinally thereof, a flexible member having connection with each section at a point adjacent to the 5 lower end thereof, said flexible members adapted to lie in the grooves when the sections are in their telescoped positions, means having connection with the flexible members for moving the flexible members to extend 10 the telescoped sections, means for moving the post from its movable support, means for securing the post against movement when in its vertical position, and means for anchoring the movable support against 15 movement.

2. In a device of the character described, a movable support, a post formed of a plurality of telescoping sections, said sections having openings formed adjacent to the up-

per ends thereof, a key positioned within 20 each opening, said key including a handle portion and depending lugs, said depending lugs adapted to embrace portions of the section associated therewith, adjacent to the openings to prevent movement of the key, 25 said keys adapted to support the adjacent upper section, means for moving the sections to their extended positions, means for moving the post from its movable support, and means for anchoring the movable support against movement.

In testimony that I claim the foregoing as my own, I have hereto affixed my signature in the presence of two witnesses.

CHARLIE ELMER BROWN.
